United States Patent Office.

JAMES MORGAN, OF PITTSBURG, PENNSYLVANIA.

Letters Patent No. 104,186, dated June 14, 1870.

IMPROVED MACHINE FOR MAKING HARROW-TEETH.

The Schedule referred to in these Letters Patent and making part of the same.

To all whom it may concern:

Be it known that I, JAMES MORGAN, of Pittsburgh, in the county of Allegheny and State of Pennsylvania, have invented a new and improved Machine for Making Harrow-Teeth; and I do hereby declare that the following is a full, clear, and exact description thereof, which will enable others skilled in the art to make and use the same, reference being had to the accompanying drawing forming part of this specification.

This invention relates to improvements in a machine for making harrow-teeth, and consists in an arrangement of a pair of pressing and pointing dies, a fin-cutter, and a cutter for cutting off the bar, all as hereinafter specified.

Figure 1 is a plan view of my machine, partly sectioned.

Figure 2 is a section on the line *xx*.

Figure 3 is a section on the line *yy*.

Similar letters of reference indicate corresponding parts.

A represents a fixed die, and

B a moving die, each having a V-shaped groove, suited to the blank to be used, which, together, terminate at *C* in a pyramidal point.

This portion, *e*, of the die is designed to point the blank, and, for that purpose, I so construct the pointing portions of the dies that they may serve the purposes of cutters or knives for removing portions of the surplus metal.

To this end the pointing portions of the dies are tapered externally on the upper and under surfaces, following lines parallel to those of the taper of the cavity, so as to reduce the walls of the die to cutting edges. Thus the dies, as they are forced toward each other, shear off two sides of the blank, and reduce it to a wedge-like form, as indicated at *d*.

These parts of the dies are formed in separate blocks, *e*, of metal, joining the other blocks, *f*, on the line *g*.

The object of making these parts separate from the others is to be able to renew them oftener than the

other parts, for they wear out sooner, in consequence of the greater wear on them in cutting and reducing the bar to form the points, while the function of the other parts is mainly only to hold the blank.

D is a fin-cutter, consisting of a steel plate with a V-notch in the end fitting over the pointed ends of the dies, and sliding back and forth over the line where the faces of the dies meet, the movement being when the dies are closed on the metal.

This cutter is mounted in the end of a slide, *E*, working on the bed parallel with the slide *F*. It is made adjustable toward the die, and carries a gauge, *D'*, to arrest the bar when fed in.

This slide *E* is operated by the same driving-shaft, *G*, which works the slide *F*, carrying the movable die. This shaft imparts motion to the slides by eccentrics or cams, *H*, working in yokes in the ordinary way of working such slides.

The dies *A* *B* are mounted in their supports in the usual way, and are provided with dischargers, *I*, and a cutter, *K*, the cutter being attached to the fixed die, so that the bar is forced against it by the movable die, and, the dischargers being attached to the die-supports, and extending across the line between the dies and hooking down into channels formed in the opposite dies, so as to catch the teeth and pull them out of the grooves as the dies separate.

Having thus described my invention,

I claim as new and desire to secure by Letters Patent—

1. The pressing and pointing dies, provided with V-grooves, terminating in a point, and tapered on the pointed ends at *d*, for cutting and flattening the point of the blank, and made in two parts, all substantially as specified.

2. The combination, with the pressing and pointing dies, of the fin-cutter, substantially as specified.

JAMES MORGAN.
